UNITED STATES PATENT OFFICE.

FRANK D. LANDER, JR., OF HIGHLAND PARK, ILLINOIS.

HAMPER.

Application filed September 28, 1922. Serial No. 591,086.

To all whom it may concern:

Be it known that I, FRANK D. LANDER, Jr., citizen of the United States, residing at Highland Park, in the county of Lake 5 and State of Illinois, have invented certain new and useful Improvements in a Hamper; and I do hereby declare the following to be a full, clear, and exact description of the invention, such as will enable others skilled 10 in the art to which it appertains to make and use the same.

My invention relates to hampers as used for shipping and storing goods, and in its general objects aims to provide a hamper 15 which will be superior to those in common use, both as to strength and durability, as to an advantageous displaying and advertising of the contents, and as to the store space required both for empty and for filled 20 hampers.

In shipping various kinds of vegetables it has been customary heretofore to employ hampers having round bottoms and round tops in preference to crates, for the reason 25 that the relatively greater height of a hamper when opened displays the contents more effectively to the intended purchaser. However, such hampers have decided disadvantages in that they waste a large 30 amount of space in the cars and storage houses and that they do not offer an adequate resistance to the severe shocks to which they may be subjected while they are being shipped in railway cars or otherwise 35 transported. Furthermore, the usual round hamper construction affords an undue number of gaps between the panels or riser portions, and if the hampers are used for shipping such articles as cured sweet potatoes, 40 some of the contents are apt to be damaged by being forced against the sharp corners of the spaces between the panels. Consequently, when ordinary hampers are used for shipping sweet potatoes, the distributing 45 jobber has to repack many of the hampers to eliminate the damaged potatoes.

My invention aims to reduce such damaging (which also commonly occurs when crates are employed for the same purpose) 50 by reducing the number of gaps between the panels and by generally strengthening the hamper. Furthermore, my invention aims to provide an inexpensive construction which will make the hamper particularly 55 strong for resisting shocks or other strains in one direction, thus enabling the user to

guard against a damaging of the hampers by so disposing them in the railway cars that the bumping of the cars will effectively be resisted. Still further and more detailed 60 objects will appear from the following specification and from the accompanying drawings, in which

Fig. 1, is a perspective view of a duly 65 labeled hamper embodying my invention.

Fig. 2, is an enlarged bottom view of the same.

Fig. 3, is a corresponding enlarged central and longitudinal section through the 70 hamper.

Fig. 4, is a perspective view of the bottom of the hamper.

Fig. 5, is a horizontal section through a corner portion of a railway car, showing 75 hampers of my invention as loaded in the same for effectively resisting the jarring of cars in transit.

Fig. 6, is a perspective view of one of the wide side panels of the hamper.

In accomplishing the purposes of my invention after the manner of the accompanying drawings, I construct the hamper primarily of veneer or thin wooden panels or riser portions connecting a substantially elliptical upper hoop with the edges of a 85 bottom board. This bottom board is symmetrical with respect to the central vertical plane B of the hoop, but is not elliptical in shape. Instead, it has two straight and desirably vertical side edges extending parallel to the said plane, and has each of its ends rounded on a radius relatively greater than that of the ellipse of a length corresponding in shape to the hoop and in length the bottom board. Thus in Fig. 2, 90 the dotted line A shows the elliptical contour which the bottom board would have if shaped to correspond to the upper hoop 1 of the hamper, while the actual ends of the bottom board 2 are curved at a much 100 smaller convexity than the ends of the imaginary ellipse A.

Connecting the bottom board 2 with the upper hoop 1 are a series of thin wooden or veneer panels which desirably extend close 105 to each other at the bottom board 2, while gapping away from each other at the hoop so as to allow the required circulation of air through the hamper. These panels desirably include two side panels 3, each of which 110 corresponds in length to one of the straight sides 4 of the bottom and is secured thereto.

They also desirably include a series of end panels 5 secured at their lower ends to the rounded ends of the bottom. All of these panels are firmly secured to the hoop 1, desirably by means of a correspondingly shaped inner hoop 6, and in doing so are made to conform in their upper portions to the adjacent parts of the hoop. In the case of the wide panels 3, this means that their lower ends 16 are straight, while their upper ends 15 are curved, thereby imparting a considerable twist to each side panel. Owing to this twist and the fact that any tendency to compress the hoop along the longitudinal axis would be resisted by the fastening of the side panels 3 to the straight sides 4 of the bottom, the hamper is particularly adapted to resist strains in this direction. Consequently, by packing the hampers longitudinally in a railway car, such as the car having the end walls 7 of Fig. 5, I enable the hampers to resist the bumping and slamming which occurs in the starting and switching of railway cars. When thus loaded after the manner of loading egg cases, it will also be evident from Fig. 5 that while the waste space is much less than with hampers of circular cross-section, this space is adjacent to the gaps in the hamper walls so that the partial flattening of the sides does not materially interfere with the circulation of air between and through the hampers.

Moreover, by employing wide side panels, I not only increase the longitudinal rigidity of the hampers and decrease the gaps in the same, but also provide large and uninterrupted surfaces for displaying labels or advertising matter relating to the contents of the hampers. Such matter can either be imprinted directly on the side panels or it can be desirably pasted on such a side panel in the form of a label 14 after the manner shown in Fig. 1, in which case the label is guarded against injury by the uninterrupted wide backing which the side panel affords. It will thus be seen that the major axes of the bottom and the hoop are in the same vertical plane and that by reason of the ends of the bottom being of less convexity than the ends of the hoop there is provided an increased area adjacent the bottom or lower end of the hamper. Furthermore, these curved ends of the bottom position the connecting end panels in an arc having an increased radius over the arc prescribed by the ends of the hoop and consequently these panels are better positioned to resist lateral compression. To close the top of the hamper, I desirably provide a wooden cover 8 shaped substantially to correspond to the hoop 1, and having a pair of stiffening cleats 9 secured to it. I then fasten the cover in position by means of straps 10 fastened between the hoop and

the side panels, these being affixed in the usual manner. I also desirably reinforce the hamper by a wire banding 11 extending around the panels intermediate of their height and by banding 12 of flat wire extending around the bottom of the panels, and desirably increase the circulation of air through the hamper by providing the bottom board with perforations 13. However, I do not wish to be limited to these or other details of the construction and arrangement thus disclosed, nor to the use of my hamper for the particular purposes mentioned. Obviously many changes might be made in construction without departing from the spirit of my invention or from the appended claims, and likewise other uses than that of shipping vegetables like sweet potatoes will readily suggest themselves.

I claim as my invention:

1. A hamper comprising a bottom having straight sides and curved ends, an elliptical hoop, and veneer panels connecting the sides and ends of the bottom with the hoop, the major axes of the bottom and the hoop being in the same vertical plane, the ends of the bottom being of less convexity than the ends of the hoop to provide an increased bottom area and to position the connecting end panels to better resist lateral compression. 85

2. A hamper comprising a bottom having straight sides and curved ends, an elliptical hoop, and veneer panels connecting the sides and ends of the bottom with the hoop, said panels including single-piece side panels each corresponding in width to the longitudinal side of the bottom, and end panels having their adjacent side walls disposed close together at the bottom and diverging upwardly to the hoop to form air gaps, the major axes of the bottom and the hoop being in the same vertical plane, the ends of the bottom being of less convexity than the ends of the hoop to provide an increased bottom area and to position the connecting end panels to better resist lateral compression. 100

3. A hamper, comprising a rigid bottom having straight side edges and curved ends, an upper substantially elliptical hoop, and panelling extending between and connecting the bottom and hoop together, said hoop being longer and wider than the bottom to make flared the upper portion of the hamper, said panelling including side and end panels secured to the corresponding portions of the bottom and hoop with the side edges of the panels diverging upward to provide ventilating gaps therebetween, there being two side panels, one on each side of the hamper and each side panel having its lower end straight and of a width corresponding to the length of the straight side edge of the bottom to which the side panel is secured. 115

4. A hamper, comprising a rigid bottom having straight side edges and curved ends, an upper substantially elliptical hoop, and paneling extending between and connecting the bottom and hoop together, said hoop being longer and wider than the bottom to make flared the upper portion of the hamper, said paneling including side paneling secured to the corresponding portions of the bottom and hoop with the side edges of the panels diverging upward to provide ventilating gaps between them, the lower ends of the side panels being straight to conform to the straight side edges of the bottom to resist end strains on the hamper, said hoop having inner and outer sections between which the upper portions of the side and end panels are secured, and banding around the hamper on the outside of the panels between their upper and lower ends.
5. A hamper comprising a rigid bottom having straight sides and curved ends, an upper substantially elliptical hoop, paneling extending between and connecting the bottom and the hoop together, said hoop being longer and wider than the bottom to make flared the upper portion of the hamper, said paneling including side panels secured to the corresponding portions of the bottom and hoop with the lower ends of the side panels substantially straight to conform to the straight side edges of the bottom, and two bands surrounding the hamper about the paneling with one band adjacent the bottom of the hamper and the other between the bottom and top of the same.

Signed at Chicago, Illinois, Sept. 26th, 1922.

FRANK D. LANDER, JR.
